HOOD CONSTRUCTION

William J. Hall, Detroit, Mich., assignor, by mesne assignments, of thirty per cent to Ollie L. Herren, thirty per cent to Joseph B. Zimmers, thirty-three per cent to William J. Hall, and seven per cent to R. C. Schemmel

Application November 23, 1932, Serial No. 643,968

11 Claims. (Cl. 180—69)

The invention relates to hinge constructions, and has particular relation to a hood, and manner of hinging the wings of the hood.

In certain respects the invention is related to those embodied in my copending applications for patent Serial No. 588,566 filed January 25, 1932, Serial No. 602,516 filed April 1, 1932, and Serial No. 608,282 filed April 29, 1932, all relating to Hood constructions.

One object of the invention is to provide a hinge construction connecting the wings of a hood, wherein one of the hinge parts embodies a finishing strip located between the hood wings and which is connected to one of them for movement therewith.

Another object of the invention is to provide a hinge construction for connecting the wings of a hood, wherein the axis of hinging movement is laterally displaced with respect to the median line of the hood, so as to permit providing a finishing strip on one of the wings which will be located centrally of the hood and movable with said wing about the axis of the hinge.

Another object of the invention is to provide a hood construction including a relatively wide finishing strip extending between the wings of the hood and centrally thereof, wherein the finishing strip is carried by one of the wings and is hingedly connected to the other for hinging movement about an axis laterally displaced with respect to the median line of the finishing strip.

Another object of the invention is to provide improved means for pivotally supporting the ends of a hinge embodying rolled interengaging edges, on stationary supports at the ends of the hinge.

And in general, it is an object of the invention to provide an improved two part hinge for pivotally connecting the wings of a hood, which will provide an attractive finishing strip between the wings of the hood, and which can be manufactured inexpensively and as an article of manufacture for ready attachment to the hood wings.

Other objects of the invention will become apparent from the following specification and the 45 claims hereinafter set forth.

For a better understanding of the invention reference may be had to the accompanying drawing forming a part of the specification wherein,—

Figure 1 is a fragmentary plan view of an automobile having a hood constructed according to one form of the invention.

Figure 2 is a fragmentary and enlarged plan view of the construction shown by Figure 1, with certain parts shown in cross section.

Figure 3 is a cross-sectional view on a larger

scale taken substantially along the line 3—3 of Figure 1.

Figure 4 is a fragmentary end view of the hood when removed from the automobile, illustrating more particularly the end portion of the hinge.

Figure 5 is a cross-sectional view taken substantially along the line 5—5 of Figure 2.

Figure 6 is an end view of the hinge.

Referring to Figures 4 and 6, hood wings 10 and 11 are illustrated, and these wings, at their adjacent edges have inwardly turned attaching flanges 12 and 13. The hinge connecting the wings of the hood comprises a male hinge member 14 having an attaching flange 15 that may be welded or otherwise suitably secured to the flange 12 of the wing 10, and a female hinge part 17 which constitutes a rolled edge portion of a finishing strip 18. The strip 18 in the particular construction illustrated, is slightly bowed intermediate its lateral edges to provide a more attractive appearance, and at that edge opposite the hinge part 17, has a flange 19 which may be welded or otherwise suitably secured to the flange 13 of the wing 11. It will be noted that this flange 19 is slightly offset as indicated at 20 to provide 25 an opening 21 generally simulating the space 22 indicated at between the outer side of the female part 17 and the junction of the wing 10 and its flange 12, when the hood is in its closed position so that in appearance both sides appear substantially the same.

The construction of the male and female parts 14 and 17 of the hinge is substantially identical to the construction of the male and female parts of the hinges illustrated and described in my co-pending applications previously identified. It might also be stated here, that the male part 14 of the hinge terminates at its free edge in an arcuate hook portion 23 nesting in the female part of the hinge, so that when either wing has been 40 moved to its open position this hook portion 23 receives the free edge of the female hinge part 17, which is indicated at 24. This is clearly illustrated in broken lines showing the wing 10 in its open position, and it will be noted that the 45 hook portion 23 has moved into engagement with the free edge portion 24 of the female part and that such free edge portion has been moved into the hook. During hinging movement of either wing, the axis of movement will occur about a 50 point generally located in the position indicated by the numeral 25. As set forth in my previous applications for patent, also, the parts of the hinge are so constructed that in opening either wing, the male part 14 of the hinge may come 55

into contact with the outer surface of the female part 17 of the hinge to a point indicated at 26 generally, but that outwardly of this point, and as shown in broken lines, the male part of the hinge will not contact with the exposed surface of the female part so that visible and exposed surfaces of the female part of the hinge will not be marred or otherwise scratched during hinging movement. Also, any portion of the male part 14 visible through the opening 2 will not contact with the female part of the hinge and be scratched during hinging movement of either wing. It will also be apparent that when either wing reaches its open position, any force or momentum tending to further open the wings will be resiliently resisted by the locking engagement between the hook portion 23 and the free edge portion 24, which causes a resilient distribution of such force through the rolled parts of the hinge and adjacent parts of the wings. In other words, the force or momentum is cushioned circumferentially of the axis of hinging movement.

The median line of the hood when it is in a closed position, substantially coincides with the line 26 of the finishing strip 18 so it becomes evident that the axis of hinging movement is offset laterally from the median line of the hood. When the hood wings are closed, it appears that the finishing strip 18 is stationary and that the wings 10 and 11 will hinge about opposite edge portions of the finishing strip, but to the contrary, the finishing strip forms part of the hinge and the axis of the hinge is at one edge thereof.

For pivotally supporting the ends of the hinge 35 on the radiator and cowl portions of a vehicle, for example, brackets 30 are provided which may be secured by bolts 31 to the under side of a flange 32 on the cowl and radiator. This bracket is, of course, only illustrative of a general type of bracket that may be used. The bracket is so disposed that it is in alignment with the finishing strip portion 18 and as far as external appearances are concerned when the hood is closed, it would appear that the hood is pivotally connected to the brackets at the center thereof. However, each bracket at a point laterally offset with respect to its center, is provided with a cylindrical opening 33, and as best shown by Figures 2 and 3, the exposed end of the bracket is closed so that the opening is not visible exterior to the hood. For pivoting the hinge in the openings 33, the male part 14 of the hinge is extended, as indicated at 34, beyond the end of the female part, as best shown by Figure 4, and is cut away as indicated at 35, Figure 6, in order to eliminate the flange 15 and that portion on the male member between the flange and the cutaway point 35. Also, as best shown by Figure 6, the extending part of the male member 34 is fashioned into substantially cylindrical form by inwardly deforming that portion of the male member between substantially the point 36 and the cutaway point 35, so that the extended end of the male member may snugly, but rotatably fit in opening 33.

65 This deformation of the male member between the points 36 and 35 applies only to the extended ends of the male member so that the deformation will not interfere at all with the hinging of the male and female parts. It might be stated also, in accordance with my previous applications for patent that the outer surface from substantially the point 36 to the point indicated at 39 has a single radius of curvature. It is apparent therefore, in deforming the male portion from point 36 to the cut off edge 35, it is only necessary to

substantially conform this portion to the curvature of the part between points 36 and 39 and to have such parts concentric.

As shown by Fig. 6, particularly, the deformed ends of the male member are such that the male and female members may be telescopically assembled and disassembled when the members have the full line positions shown in this figure. It is evident that the gap between edges of the projecting ends is such as to allow this assembly and disassembly. However, as wing 10 begins and continues to open, the lower turned in edge portions of the projecting ends of the male member pass over end faces of parts of the female member, and when the parts are so related, relative axial movement of the members is prevented. The same condition is effected when wing 11 opens.

It will be noted as shown best by Figure 2, that the wings at each end extend beyond the ends of the strip 18 and are notched as indicated at 37 and 38, for permitting the wings to extend over and embrace opposite end portions of the brackets 30. Normally the end of the finish strip will substantially abut the adjacent sides of the brackets 30 with the extended portions of the male hinge part projecting into the openings 33. This type of arrangement maintains the male and female parts of the hinge in proper axial positions and prevents axial movement, one with respect to 30 the other during any hinging movement of either wing.

It will, of course, be appreciated from the description and illustration, as shown by Figure 1 particularly, that to all external appearances, 35 the hood resembles that type having a stationary finishing strip between the wings of the hood, which ordinarily is chrome plated. To the ordinary observer, it would not be apparent that this finishing strip is intended to move except 40 upon opening the wing to which it is secured. When the hood is closed, it is not apparent that the axis of hinging movement is at one side of the median line of the finishing strip, nor is it apparent that this finishing strip will pivot about 45 the offset axis. It will also be appreciated that the flanges, 12 and 13, 15, 19 extend only between the brackets, and that when the wings are closed such flanges project downwardly between the brackets. 50

Preferably the hinge will be manufactured as an article to be subsequently attached to the flanges 12 and 13 of the hood wings manufactured by the motor vehicle manufacturer, and the exposed parts at least of the hinge such as 65 the exposed surfaces of the female part, finishing strip and that part of the members visible through the openings 21 and 22, may be chrome plated or otherwise decorated to enhance the appearance of the hood. 60

Although only one form of the invention has been illustrated and described in detail, it will be apparent to those skilled in the art that various modifications may be made without departing from the scope of the appended claims. 65

I claim:

1. A hood hinge comprising a finishing strip, terminating at one edge in an attaching flange directed to one side thereof, and its other edge in a rolled edge at the same side of the strip as 70 the flange, and a second member having an attaching flange similar to the first flange, and a rolled edge portion hingedly cooperating with the rolled edge on the finishing strip, the axis of hinging movement of the cooperating rolled 75

- edges being substantially offset from the line median between the edges of the finishing strip.
2. In combination with a vehicle having radiator and cowl portions, a hood for the vehicle, comprising hood wings, a finishing strip extending between the wings, means for operatively connecting the wings and finishing strip, for hinging movement about an axis offset laterally from the median line of the strip, and means for hingedly supporting the wings and strip on the radiator and cowl portions.
3. In combination with a vehicle having radiator and cowl portions, a pair of hood wings having adjacent edges disposed in substantially equally spaced relation to the median line of the cowl and radiator portions when the hood is closed, a finishing strip disposed between such edges of the wings, means connecting one wing to one edge of the finishing strip, and means for hingedly connecting the finishing strip and other wing and pivotally supporting the hood on the radiator and cowl portions, for hinging movement about an axis offset laterally from said median line.
4. In combination, a vehicle having radiator and cowl portions, a pair of hood wings, and means for hingedly connecting the wings and pivotally supporting them on the cowl and radiator for hinging movement about an axis offset laterally from the longitudinal and vertical median plane of the cowl and radiator, the wing at the side of the median plane opposite the axis, embodying a finishing strip extending symmetrically to opposite sides of the median plane and at the upper side of the hood when the latter is in closed position.
5. In combination, a vehicle having radiator and cowl portions, a pair of hood wings, and means including interengaging rolled edge portions at adjacent edges of the wings for hinging them on the radiator and cowl portions about a common axis offset laterally from the longitudinal and vertical median plane of the radiator and cowl.
6. A hinge comprising a generally flat and elongated strip having an attaching flange at one edge directed to one side of the strip, and having a portion at its other edge rolled toward the same side of the strip, to provide a hinge part, and a second member having a rolled portion hingedly interengaging the rolled portion on the strip, and an attaching flange directed similarly to the first flange, said flanges, with the hinge in one position, being disposed in parallel and substantially equally spaced relation to the center of the strip.
7. A hinge comprising plate members having turned, interfitting edges hingedly connecting the members, and which are assembled by longitudinally telescoping the edges, one of such edges projecting beyond the other to provide pivot portions adapted to be pivotally mounted on supports, and means on such projecting ends for preventing telescopic assembly or disassembly of the edges except when the plates are in predetermined hinging relation.
8. A hinge comprising plate members having turned, interfitting edges hingedly connecting the members, and which are assembled by longitudinally telescoping the edges, one of such edges projecting beyond the other to provide pivot portions adapted to be pivotally mounted on supports, said projecting edges being substantially cylindrical and normally preventing telescopic assembly and disassembly of the members, but having a longitudinal gap in the walls thereof to permit assembly and disassembly of the members in a telescopic manner when they are in predetermined hinging relation.
9. A hinge comprising plate members having turned, generally spiral interfitting edges hingedly connecting the members, and which are assembled by longitudinally telescoping the edges, one of such edges projecting beyond the other to provide pivot portions adapted to be pivotally mounted on supports, and means on such projecting ends for preventing telescopic assembly or disassembly of the edges except when the plates are in predetermined hinging relation.
10. In combination with a vehicle having radiator and cowl portions, a pair of hood wings, and means for hingedly connecting the hood wings and pivotally mounting them on the radiator and cowl portions, said means comprising a finishing strip extending between adjacent edges of the wings and terminating at one edge in an attaching flange rigidly connected to one of the wings, a second member at the other edge of the strip and having a similarly directed attaching flange, means hingedly connecting the second member to said other edge of the strip, and means rigidly connecting the second attaching flange to the other wing.
11. In combination with a vehicle having radiator and cowl portions, a pair of hood wings, and means hingedly connecting the wings and pivotally mounting them on the radiator and cowl portions, said means comprising a finishing strip extending between adjacent edges of the wings and having an attaching flange at one edge rigidly connected to one of the hood wings, the other edge of the strip being rolled to provide a hinge part, and a second hinge part having a rolled edge interengaging the rolled edge of the finishing strip and having a similarly directed attaching flange rigidly connected to the other hood wing.

WILLIAM J. HALL.
